CONTAINER FOR MILK BOTTLE CAPS

William A. Davis, Hamilton, Ontario, Canada, assignor to Smith-Lee Company, Oneida, N. Y.

Application January 20, 1940, Serial No. 314,866

1. Claim. (Cl. 206—46)

This invention relates to an improved tubular container for milk bottle caps.

An object is to provide a container for milk bottle caps which is simple, strong, and inexpensive. It may be easily fabricated and it is so constructed that the bottle caps carried therein will be protected against contamination by dirt, dust, moisture, or other foul material and to an appreciable degree from bacteria.

The container embodies a tubular body portion and end closures for said body portion. Such body and end closures may have a structural foundation of any suitable material. Paper is suitable and may be used. The tube may take any cross-sectional shape and it is understood that wherever the words "tube" or "tubular" are used herein such words describe, unless otherwise specified, a hollow tubular structure having any desired cross sectional shape.

More particularly, the container is so constructed that it includes a protective coating or lamination which is substantially impervious or resistant to the passage therethrough of moisture, foul material, or bacteria. Preferably this coating or lamination forms a part of each end closure as well as a part of the body portion of the container. Such coating may be of any suitable character. A wax like coating has been found satisfactory. The coating may be formed of a thermoplastic moisture resistant substance or the substance may be rendered adhesive by a solvent rather than heat. Substances such as paraffin wax, or other suitable waxes, resinous substances, or the like, may be employed.

In one preferred form the coating extends over the inner face of the tubular body and each end closure. The coating may, however, be associated with the outer face of the container or it may constitute an intermediate layer or lamination which is moisture resistant. The container may be so formed that the impervious coating associated with the end closure is hermetically sealed to the coating associated with the tubular body portion thereby forming a continuous impervious protective layer.

Furthermore, the container is of such a character as to facilitate dispensing the caps therefrom when the caps are to be used in a bottle capping machine.

This application is a continuation in part of application Serial No. 261,023, filed March 10, 1939.

Other objects, advantages and meritorious features of my invention will more fully appear from

the following description, appended claim, and accompanying drawings, wherein:

Figure 1 is a perspective of a container tube embodying my invention.

5 Fig. 2 is an elevation of one end of the tube, Fig. 3 is a sectional view through the opposite end of the tube,

Fig. 4 is a sectional view through that end of the tube shown in Fig. 2,

Fig. 5 is a perspective of a container of a construction similar to that of Fig. 3 except that it is square in cross section and the protective coating is disposed on the outside,

Fig. 6 is a cross-sectional view through the structure of Fig. 5, and

Fig. 7 is a cross-sectional view through another modified form of construction.

Heretofore milk bottle caps have been packaged for shipment and storage in open end paper tubes. The wall of the tube was crimped inwardly at each end to hold the caps in place therein. When the caps were desired for use one end of the tube was cut off inwardly of the crimped over wall so as to promote free slideable discharge movement of the caps from the tube through the capping machine. Caps so packaged were open to fouling and contamination. Dirt, moisture, and bacteria collected thereon prior to their use and during shipment and storage.

I propose to provide a tubular container which will keep the caps in a sanitary, sterile, condition and protect them from deposit of bacteria or other foul injurious material thereon prior to their use and which will facilitate the dispensing of the caps from the tube for use.

My container tube 10 may be formed of paper rolled up in the conventional spiral manner. It is common practice to form such tubes of a plurality of paper layers adhesively secured together. I propose to so fabricate such a tube that it embodies a coating or lamination which is impervious or resistant to the passage of moisture or other material therethrough. Such coating may be formed of any suitable moisture resistant substance.

Paraffin wax has been found suitable. It is relatively inexpensive and thermoplastic. Other waxes or resins may, however, be employed. Such coating need not be thermoplastic but it must be moisture resistant to constitute a protective layer. Its adhesion might be obtained through use of a solvent or it might be thermosetting.

The coating is preferably applied to the inner

face of the tube and when a wax like substance is applied to the inner face of the paper tube it not only forms a moisture resistant coating over such inner face but it seals up in the body structure of the tube bacteria that may be present therein. Applied as a hot melt coating the heat will destroy many of the bacteria and will inhibit movement of others through the coating.

In the drawing the paper wall structure of the container tube is indicated as 10 and the impervious or resistant protective coating or lamination is indicated as 12. In Figs. 3 and 4 this coating 12 is indicated as applied to the inner surface of the tube and that surface of each end closure which is exposed to the interior of the tube. The coating applied as a hot melt coating impregnates the paper and also forms a surface coating thereover to serve the purposes hereinabove set forth.

In these first four figures of the drawing, which illustrate the preferred form of construction, the tube is formed of two plies of paper spirally wound and adhesively sealed together in a manner well known. The inner ply is impregnated with moisture resistant coating material which also forms a protective layer over the inner face of such ply. Each end closure is formed of paper which is also impregnated with a suitable coating compound that covers its inner surface.

In Fig. 6 this coating 12 is shown as applied to the outer surface of the tube body and the end closures instead of to the inner surface as in Figs. 3 and 4. The closed end tube may be dipped into a coating bath.

In Fig. 7 the tubular body is shown as formed of two layers of structural material 10, which layers may be paper, and between which is disposed an intermediate layer 12, which intermediate layer constitutes the resistant protective layer and also adheres the two structural layers together. This intermediate layer may be a suitable moisture resistant adhesive substance such as vinyl acetate, vinyl chloride or a co-polymer of the two or any other suitable moisture resistant adhesive, serving both as an adhesive between the two plies 10 and as an impervious coating or layer 12. Such intermediate layer 12 may be a paper sheet impregnated with a moisture resistant substance such as the vinyl acetate or vinyl chloride mentioned which not only renders the sheet substantially impervious to the passage of moisture and foul material therethrough but also upon heating to the point of adhesion forms an adhesive bond with the two structural plies 10.

The resin compositions such as vinyl acetate or vinyl chloride or a co-polymer of the two might be used instead of wax as a coating for one surface of the tube. They are thermoplastic. Other suitable moisture resistant thermoplastic or thermosetting substances might be used. A substance responsive to a solvent for adhesion might be employed. The vinyl resins mentioned respond to alcohol and would be suitable for such use. Many other suitable moisture resistant substances are known.

A closure cap is provided for each end of the tube. In the construction shown one closure cap 20 is illustrated as secured within its end of the tube. The tube is then filled through the opposite end with bottle caps 18. Commonly these caps are formed of paper. The caps are wax treated prior to being packaged within the tube. They are packaged while in a heated state. Following the filling of the tube with

caps the opposite end closure 14 is secured to its end of the tube and sealed in place.

In the construction shown in Figs. 3 and 4 the end closure 20 which is secured in place before the tube is filled with caps is illustrated as cup-shaped and as having a side wall portion 21. This end closure is shown as provided with a protective moisture resistant coating or lamination 12 extending over its outer surface which is the end face and side wall surface that lies within the tube when the end closure is in position. The side wall of the tube body is shown as rolled or spun over at 22 upon and over the side wall 21 of the end closure holding such end closure in place.

While the relatively impervious layer 12 is shown as extended over that face of each end closure within the tube in Figs. 3 and 4 it is illustrated as extending over the outer face thereof in Fig. 6 and as constituting an intermediate layer thereof as described in connection with the structure of Fig. 7.

In the construction shown in Figs. 3 and 4 the coating layer 12 over the side wall 21 of the inserted end closure is preferably sealed to the coating layer 12 over the inner surface of the tubular body. This would form a hermetic seal at such point.

The end closure cap 14 is also shown as cup-shaped. It is received over the outside of its end of the tube instead of being seated within the tube. This closure cap is provided with a protective coating layer 12 which in Figs. 3 and 4 is shown as extending over the inner surface. In the constructions of Figs. 6 and 7 this moisture resistant coating or layer constitutes an outer layer and an intermediate layer, respectively, as hereinabove described.

This closure cap 14 is received over that end of the tube through which the bottle caps were inserted and after the tube is filled with bottle caps. It is sealed in place in any suitable manner. In Fig. 3 it is shown as so sealed by an adhesive band 16, which band may be a crepe paper masking tape which, because of its extensibility, could be snugly drawn about the diameter of the cap and about the diameter of the tube though these diameters are different. Obviously other bands might be employed and they might be differently affixed so long as the cap was properly secured in place.

I prefer to package the milk bottle caps while they are hot from the wax with which they have been treated. One common practice is to impregnate them with paraffin wax compound at a temperature of approximately 240° F. The impregnating wax is pressed into the caps so as not to leave any excess of wax upon the outer surface. It is obvious that other suitable substances might be used. There are many waxes and resins which are suitable.

As the caps are disposed within the tube while in the heated state the retained heat of the packaged caps confined within the tube has a tendency to heat seal the wax coating of the two end closures to the wax coating over the inner side wall of the tube when the construction is of the character shown in Figs. 3 and 4 thereby providing a complete moisture proof coating or layer about the contained bottle caps retaining such caps in a sterile sanitary condition until used. Whether such seal resulted would depend upon the amount and character of the coating and the contained heat, but in any event the protective coating associated with the wall of the tube and

the end closures would constitute a highly effective protective envelope about the caps within the container.

The atmosphere in dairies wherein the caps are used is heavily moisture laden. It is common practice to provide milk bottle caps with lift tabs which are stitched in place by steel wires. This moisture has a tendency to attack and rust the wires. Packaging the caps as herein described protects them from attack by such moisture and consequent rusting.

Dairies generally make use of many different kinds of milk bottle caps. These caps are printed to indicate the particular kind of milk within the bottle with which the cap is used. To readily identify the particular kind of cap within any particular tube I prefer to insert within the cup shaped end closure 20 a single bottle cap 18 with its printed side exposed to view. This cap is held place within the end closure 20 by the crimped over side wall 22 of the tube as shown particularly in Figs. 2 and 4.

When the end closure 14 is removed from the body of the tube the contained caps may be

readily discharged from such end of the tube for use in a bottle capping machine. The opposite end of the tube having its side wall crimped inwardly would not lend itself to such discharge of caps therethrough.

What I claim:

A container tube for milk bottle caps having a cup shaped end closure inserted within one end of the tube, the wall of the tube at such end being rolled over within the tube overlapping the side wall of such end closure holding said end closure in position, an external end closure received over and secured to the opposite end of the tube, said tube and each end closure being provided with a moisture resistant protective coating, the tube coating being thermoplastically hermetically sealed to the two end coatings forming a continuous homogeneous layer therewith, and a milk bottle cap seated upon the outer face of the inserted end closure and held in place thereon by the side wall of the tube being rolled over inwardly thereagainst.

WILLIAM A. DAVIS.
